UNITED STATES PATENT OFFICE.

CHARLES McMANUS, OF BELLEVILLE, ILLINOIS.

AUTOMATIC CONTROL DEVICE FOR LIQUID-FUEL BURNERS.

Application filed June 22, 1925. Serial No. 38,871.

This invention relates to automatic control valves particularly adapted for use with liquid fuel burning systems and has for its principal object to provide means for preventing further flow of liquid fuel to the burner after the liquid fuel has reached a predetermined level therein. Other objects are to provide an inexpensive control valve that will enable the flow of liquid fuel to the burner to be easily and accurately controlled, that will have a simple and compact construction, and that will prevent leakage around the valve stems.

The invention consists principally in means adapted, when the liquid reaches a predetermined level in the liquid fuel burner, to divert liquid fuel flowing to the burner into a container operatively connected with a control valve so that the weight of the liquid fuel thus diverted serves to close said valve and thus stop further flow of liquid fuel to said burner. It also consists in an improved control valve and in the mechanism for actuating the same; and it also consists in the combinations and arrangements of parts hereinafter described and claimed.

In the accompanying drawing, which forms part of this specification, and wherein like symbols refer to like parts wherever they occur,

Fig. 1 is a vertical sectional view of a liquid fuel burner equipped with an automatic control device embodying my invention, the control valve being shown in elevation and in open position;

Fig. 2 is an end elevation of the control valve, the valve being shown in closed position;

Fig. 3 is a view similar to Fig. 2 looking towards the opposite end of the control valve; and

Fig. 4 is a central vertical section through the control valve on the line 4—4 in Fig. 1.

Referring to the accompanying drawing, my invention is shown in connection with a liquid fuel burner A of ordinary form which is supplied, by gravity or other pressure, with oil from a supply tank (not shown) by means of a supply pipe comprising a section 1 leading from the supply tank to the inlet chamber 3 of a control valve B and a section 2 leading from the outlet chamber 4 of said control valve to said burner.

The control valve B is supported in a horizontal position on a pedestal 9 and comprises a main body portion 10 having cylin-

drical recesses in its opposite ends which form part of the inlet chamber 3 and the outlet chamber 4 and are covered by hemispherical caps 11 removably secured in place 60 by screws 12. These recesses communicate with each other through a central bore or passageway 13 which extends through the wall which separates said chamber. The opposite ends of the passageway 13 are provided with conical seats for the tapered ends of a horizontally disposed shut-off valve 14 and a regulating valve 15. The needle valves 14 and 15 are keyed or otherwise non-rotatably supported in axially aligned bores extending through horizontally spaced bosses on the caps 11 and yokes 16 extending from top to bottom thereof.

Mounted on the respective needle valves 14 and 15, in spaces provided therefor between the bosses that slidably support said valves, are adjusting wheels 17 and 18 which have screw threaded engagement with said needle valves, whereby rotation of either of said wheels causes the needle valve controlled thereby to move in the direction of its axis and thus open or close the end of the passageway 13 engaged thereby. Interposed between the ends of the main body portion 10 of the control valve and the caps 11 therefor are metal diaphragms 19 whose marginal portions are clamped between the body and cap members by the screws 12 that secure said caps in place.

The metal diaphragms 19 are perforated 90 to receive the inner ends of the valve stems 14 and 15 and are provided with integral collar portions 20 and separate clamping rings 21 between which the central portions of said diaphragms are tightly clamped by means of screws 22. The diaphragms, which are resilient enough to permit the required sliding movement of the valve stems, serve to cooperate with the recesses in the body member of the valve to form the inlet chamber 3 and the outlet chamber 4 that communicate with each other through the passageway of port 13. It is noted that these metal diaphragms prevent leakage of oil around the valve stems and, at the same time, eliminate the use of stuffing boxes which require re-packing at frequent intervals.

The supply pipe section 2 leading from the outlet chamber 4 of the control valve B to the liquid fuel burner A communicates with said chamber at the top thereof and extends horizontally therefrom and thence

upwardly and enters said burner through the bottom thereof. The supply pipe section 2 is also provided with a branch pipe which extends upwardly to the maximum oil level 5 desired for the oil in the fuel burner (such level being indicated by the dotted line in Fig. 1) and is thence rebent downwardly in the form of a return bend 2^a.

Mounted for vertical swinging movement 10 in the bifurcated end of an arm 23 secured to the cap member which supports the cut-off valve 14 is a latch member 24 comprising an outwardly extending arm 25 adapted to support a container 26 in position to receive oil 15 discharged from the return-bend 2^a and an upwardly extending arm 27 provided at its upper end with a horizontally journaled roller 28. The latch member is also provided with a finger 29 which extends beneath the 20 yoke 16 that supports the cut-off valve and serves to limit the downward swinging movement of said member. The adjusting wheel for the cut-off valve 14 is provided with a radially extending projection in the form of 25 a pin 30 adapted to be inserted in any one of a series of holes 31 in the peripheral surface of said wheel.

The hand-wheel for the cut-off valve is also provided with a counterweight 32 adapted to 30 rotate said wheel in the direction required to close said valve. The counterweight 32 is provided with a threaded stud 33 adapted to engage any one of a series of holes 34 provided therefor in the peripheral surface of 35 the adjusting wheel. The roller 28 on the upwardly extending arm of the trip member 24 is adapted, in the open position of the shut-off valve 14, to hook over the pin 30 projecting from the adjusting wheel therefor 40 and thus retain the bucket supporting arm of said trip member in a substantially horizontal position. The counterweight 32 is located on the side of the adjusting wheel opposite the pin 30 and thus serves to press 45 said pin against the under side of the roller on the upwardly extending arm of the trip member and thereby releasably retain said trip member in its raised or normal position.

Assuming the parts to be in the position 50 shown in Fig. 1, the operation of the control device is as follows:

Oil is supplied to the inlet chamber 3 of the automatic control valve B, through the section 1 of the oil supply pipe and passes 55 through the passageway 13 into the outlet chamber 4 and is thence conducted to the burner A through the supply pipe section 2 leading thereto. In the event that the flame of the burner is accidentally extinguished, or 60 that oil enters the burner faster than it can be consumed, such excess oil will rise in the return bend branch 2^a of the section 2 of the supply pipe and be discharged into the container or bucket through the downwardly 65 extending branch of said return bend and

thus prevent the level of the oil in the burner from rising above the level of the rebent portion of said return bend. This operation continues until the weight of the oil in the bucket is sufficient to overbalance the weight 70 of the counterweight on the adjusting wheel for the cut-off valve, thereby causing the roller on the trip member to ride off the retaining pin on the pin wheel. Upon release of the pin, the counterweight swings down- 75 wardly and thus rotates the hand wheel a distance sufficient to close the opening in the passageway 13 and thereby stop the flow of oil through the section 2 of the supply pipe.

The above described control device is 80 simple and it is very easily assembled and installed. It secures a positive operation of the cut-off valve without the use of separate springs or a separate overflow pipe leading from the burner to the valve; and it also 85 controls the flow of oil to the burner in such manner that only the quantity of oil intended for consumption is permitted to enter the burner.

Obviously, the hereinbefore described de- 90 vice admits of considerable modification without departing from the invention and I do not wish to be limited to the precise construction shown. For instance, the ad- 95 justing wheel of the regulating valve which regulates the flow of oil to the burner can be automatically controlled by means of a thermostat.

What I claim is:

1. An automatic control device for a 100 liquid fuel burning system comprising a liquid fuel burner, a fuel supply pipe and an overflow pipe communicating with said burner, a rotary cutoff valve in said supply pipe, a wheel mounted on the stem of said 105 valve, a counterweight circumferentially adjustable on said wheel for rotating the same in the direction required to close said valve, a circumferentially adjustable pin on said wheel, a pivotally mounted lever having a 110 laterally extending arm and an upright arm adapted to be swung into engagement with the pin on said wheel in the opened position of said valve to prevent closing thereof, and a container mounted on the 115 laterally extending arm of said lever in position to receive the liquid discharged from said overflow pipe, said lever being adapted to be actuated by the weight of a predetermined amount of liquid in said 120 container to disengage the upright arm from the pin on said wheel and thereby permit said valve to close.

2. An automatic control device for a 125 liquid fuel burning system comprising a liquid fuel burner, a fuel supply pipe and an overflow pipe communicating with said burner, a rotary cutoff valve in said supply pipe, a counterweighted wheel attached to the stem of said valve and normally tending 130

- to close the same, said wheel being provided with a radially extending projection, a horizontally pivoted lever having a laterally extending arm and an upright arm provided with a roller adapted to engage the radial projection on said wheel in the open position of said valve to prevent closing movement thereof, and a container supported on the lateral arm of said lever in position to receive liquid discharged from said overflow pipe, said lever being adapted to be actuated to disengage the roller thereon from the projection on said wheel by the weight of a predetermined amount of liquid in said container.
3. An automatic control device for a liquid fuel burning system comprising a liquid burner, a fuel supply pipe and an overflow pipe communicating with said burner, a rotary cutoff valve in said supply pipe, a counter-weighted wheel attached to the stem of said valve and normally tending to close the same, a circumferentially adjustable pin on said wheel, a horizontally pivoted lever having a laterally extending arm and an upright arm provided with a roller and adapted to engage the pin on said wheel in the open position of said valve to prevent closing movement thereof, a container supported on the lateral arm of said lever in position to receive liquid discharged from said overflow pipe, said lever being adapted to be actuated to disengage the roller from the pin on said wheel by the weight of a predetermined amount of liquid in said container, and means for limiting the swinging movement of said lever after the disengagement of said roller and said pin.

Signed at Belleville, Illinois, this 18th day of June, 1925.

CHARLES McMANUS.
